UNITED STATES PATENT OFFICE.

JOHN F. KELLY, OF PITTSFIELD, MASSACHUSETTS.

MUSICAL ACCENTING DEVICE.

1,086,537.

Specification of Letters Patent.

Patented Feb. 10, 1914.

Application filed June 19, 1911. Serial No. 633,995.

To all whom it may concern:

Be it known that I, JOHN F. KELLY, a citizen of the United States of America, residing at Pittsfield, in the county of Berkshire and State of Massachusetts, have invented new and useful Improvements in Musical Accenting Devices, of which the following is a specification.

This invention relates to improvements in accenting devices for use in connection with musical instruments and particularly to musical instruments which are operated by means of a movable music or note sheet in which are formed openings or perforations representing the various notes or tones of the piece of music that is to be played.

The object of my present invention is to provide suitable devices for causing the melody or other notes of a piece of music to be struck with a greater force than the accompaniment notes of the piece. The action which sounds the melody notes is not set in motion until a short interval of time after the action of the accompaniment notes is set in motion. This interval of time between the setting of the action in motion which sounds the accompaniment notes and the setting in motion of the action which sounds the melody notes is so short that the accompaniment notes are not actually struck or sounded until at or about the same instant that the melody notes are struck. The means which operates the melody action is operated by a current whose electromotive force is greater than the electromotive force which operates the action of the accompaniment notes. The melody action is operated by a stronger current and moves, of course, faster than the accompaniment action but is so timed as to catch up or overtake the movements of the accompaniment action and thus cause the two sets of notes to be sounded at practically the same instant, whereby the melody notes are properly accented. In order to accomplish this very much desired result in piano players which are controlled by a note sheet, I have devised an apparatus to carry into effect these operations by means of which the melody action is moved faster than the accompaniment action, but on the other hand is set in motion a short interval of time after the latter action.

In the drawings forming part of this application, Figure 1 is a general diagrammatic view showing the arrangement of electrical connections which extend from

the key-actuating magnets of the musical instrument to the switches for closing the circuits to said magnets which operate the accompaniment and melody notes; also showing the accent switch device for controlling the circuit to an electromagnet by means of said device which is connected to the source of electrical energy at different potential points whereby different strengths of current may be cut into the circuit for changing the quantity or volume of the tone of the melody notes. Fig. 2 is a diagrammatic view of a music or note sheet illustrating the slots of the accompaniment and melody notes and the accent slots for effecting the opening and closing of the circuit to the switch-operating electromagnet.

Referring to the drawings in detail, *a* designates a battery or other suitable source of electric energy; *b* an electromagnet, one terminal of the battery being connected to one terminal of the electromagnet by means of the wires *c* and *d*; *e* designates a wire leading from the other terminal of the electromagnet to the circuit-closing device *f* which is designed to be closed by means of the movable finger members *g*, the points *g*¹ of which drop through the accent slots 14 in the note sheet *h*, causing the wire *i* to be carried into engagement with the contact bar *j* thus closing the circuit to the wire *k* which extends back to the other terminal of the battery or other source of electrical energy. The armature *m* of the electromagnet is provided with a circular contact piece *o* which slides on the contact pieces *p*, *q*, and *r*. The distance between the contact pieces *q* and *r* is such that the circuit is always closed during the movements of the circular contact piece *o*.

*m*¹ designates a bar, over which the note sheet *h* passes, that is provided with recesses *m*² therein to receive the points *g*¹ when they pass through the openings in the music or note sheet.

It will readily be seen that when the circular contact piece *o* passes from the contact *q* to the contact *r* the voltage of the current that is impressed upon the circuits leading to the two sets of key-actuating magnets will be increased since the wires *s* and *t* are connected to the battery at different potential points.

z designates a switch lever that is connected to the wire *c* and engages the contact *z* and controls the current to the wire

4 which leads from the striking magnets 5 that play the accompaniment notes. 6 is a wire that leads to the key-actuating magnets 5 through the circuit closing devices 7 which drop into the accompaniment slots 8 in the sheet that designates these notes. 9 is a switch also connected to the wire *e* by means of the contact point 10, its opposite end being connected to a wire 11 that leads 10 from the key-actuating magnets 12 which operate the keys of the melody notes. The position of the switches 2 and 9 determines the current strength in the magnets 5 and 12. The circuits to the magnets 12 are 15 closed by the switch points shown at 13, which cause the wires *i* to engage the bar *j*. The bar *j*, it will be observed, is a common contact for the three circuit closing devices *f*, 13 and 7. It is also clear that the position of 20 the circular contact member *o* will determine the strength of the current in the magnets 5 and 12.

Referring now to Fig. 2, which illustrates the note sheet for controlling the operation of 25 the accenting devices: It will be observed that the accent slots 14, or the slots which close the circuit to the electro-magnet *b* for changing the voltage of the current supplied to the key-actuating magnets are cut in the 30 note sheets *h* on substantially the same line as the beginning of the accompaniment notes 8, (although this position of the slots 14 is not absolutely necessary) which line is indicated by the numeral 15, and that the 35 melody slots are cut back from the line 15 a short distance, as indicated at 16, producing a short interval of time between the setting in motion of the action which sounds the accompaniment notes and the action which 40 sounds the melody notes, the first action being moved by the current from the lower electromotive force and the second action by the current from the higher electromotive force. It will therefore be seen that 45 when the circuit through the magnet *b* is closed by means of the accent slots 14 in the note sheet when the points *g*¹ drop therethrough, that the circular contact piece *o* is moved from the contact *g* to the contact 50 *r*, and when the points 17 of the switch elements 13 fall into the melody slots 18 a higher electromotive force will be impressed upon, and a stronger current will flow to, the key-actuating magnets 12 which sound 55 the melody notes; that is to say, the stronger electric currents will flow to the magnets 12 which operate the melody notes 18, such stronger current not coming into action until after the accompaniment action has first 60 been set in motion (but has not yet sounded its notes). The action which sounds the melody notes is started in motion a little later in time than the accompaniment notes, as shown by the space 16 on the note sheets. 65 The movements of the two actions are such

that they will both strike their respective note strings at substantially the same instant at which instant the melody action imparts a stronger blow so as to properly accent the accompaniment notes of the 70 measure.

Referring briefly to the operation of the accenting device, it will be observed that when the accenting slot 14 causes the point *g*¹ to allow the bar *i* to engage the contact bar *j*, that current will flow by means of the wire *s* from the battery *a* to the wire *k* and return by means of the wire *e* through the electromagnet *b* to the other pole of the battery. This causes the armature *m* to 80 be attracted and the circular contact piece lifted so as to engage the contact *r* whereby the current of higher voltage will flow by means of the wire *k* to the common contact bar *j* and when the slot 18 of the note sheet permits the point *g*¹ to drop the circuit will be closed from the bar *j* to the melody striking magnets 12 and return by means of the wire 11 to the other pole of the battery. The current to the accompaniment notes 90 which are actuated by means of the key-actuating electro-magnets 5 is by means of the wire *t* from one pole of the battery *a*, wire *k* to the common contact bar *j*, circuit closing device 7, wire 6 to the key-actuating 95 magnets 5 and the return wire 4 to the other pole of the battery *a*; it will be seen from the diagram shown in Fig. 1 and the arrangement of the slots in the note-sheet in Fig. 2 that the accenting slots 14 and the accompaniment slots 8 cause the simultaneous energization of the switch magnet *b* and the key-actuating magnets 5 and that after the bar *o* has been moved from the contact-piece 100 *g* to the contact-piece *r* a current of greater 105 voltage will flow to the key-actuating magnets 5, and then later, as the note-sheet is moved, the melody-slot 18, which is cut slightly back of the slots 8 and 14, will effect the closing of the circuit-closing device 110 13 and cause the melody-key actuating magnets 12 to be actuated with greater force.

No claim is made on the note sheet itself as the arrangement of cuttings therein is believed to be old in the prior art.

It is to be understood that by the term "key-actuating" I do not refer specifically to the operation of a musical instrument by means of a key, as it is clearly within the province of my invention to directly operate 115 the action of the instrument without making use of the keys at all, and the invention is not to be understood as being limited to the operation of the instrument by means of a key.

What I claim is:—

1. An electrically-operated musical instrument, comprising, in combination, actuating magnets, connections therefrom to a source of electrical energy, an electrically- 130

operated switch-device, a plurality of contact members, connections therefrom to different potential points of said source of electrical energy, a single contact member, 5 a connection therefrom to the actuating magnets, a contact-device operated by the switch-device to connect and disconnect one of the plurality of contact members with the single contact-member, a plurality of 10 circuit-closing devices interposed in the connection from the single contact-member to the different actuating magnets, a perforated note-sheet, two of the perforations therein positioned to permit the simultaneous 15 closure of a branch connection to the electrically-operated switch-device and another branch connection to one of the actuating magnets, and another perforation in the note-sheet and positioned back of the 20 two first-mentioned perforations to close another branch connection to another one of the actuating magnets later in time than the first-mentioned branch connections are closed, to cause the latter actuating magnet 25 to operate during the period the first-mentioned actuating magnets are operated, whereby the switch-device will close a connection which is connected to a higher potential point of the source of energy to 30 cause the second-actuating magnet to operate with greater strength than the first-mentioned actuating magnet, and whereby the tone produced by the action of the second actuating magnet will be louder than that 35 caused by the action of the first actuating magnet.

2. An electrically-operated automatic piano-player, comprising, in combination, a source of electrical energy normally connected with a low-potential point thereof to an electro-magnetically-operated switch-device which is normally closed, a connection

from a high-potential point of the source of electrical energy to a normally-open contact of said device, actuating devices, branch 45 connections from the normally-closed switch-device to independent electrically-operated actuating devices, a note-sheet to control the closure of said branch connections to the switch device, the closure of the 50 normally-open connection to the magnet of the switch-device to cause said device to effect the closure of the connection to the higher potential connection of the source of electrical energy, whereby a second actuating 55 device may be operated with greater strength before the first actuating device has ceased to operate, and whereby an accent effect is produced, as described.

3. An electrically-operated automatic piano-player, comprising, in combination, a source of electrical energy connected with a point thereof of normal working voltage to an electro-magnetically-operated switch-device which is normally closed, a connection 60 from a point of different potential of the source of electrical energy to a normally-open contact of said device, actuating devices, branch connections from the normally-closed switch-device to independent electrically-operated actuating devices, a note-sheet to control the closure of said branch connections to different potential points of the source of electrical energy and to said 65 actuating devices in succession and to the normally-open connection to the magnet of the switch-device to cause said device to cause the closure of the connection to the point of different potential connection of the source of electrical energy. 70
